UNITED STATES PATENT OFFICE

WALTER VAN B. ROBERTS, OF PRINCETON, NEW JERSEY, ASSIGNOR TO RADIO CORPORATION OF AMERICA, A CORPORATION OF DELAWARE

RADIO RECEIVING CIRCUIT

Application filed April 17, 1930. Serial No. 444,980.

My present invention relates to radio receivers, and more particularly to a receiving circuit embodying a novel type of direct coupled amplifier.

5 In the receiving circuit art, resistance-coupled audio amplification has always been connected with optimum reproduction quality. However, due to the lack of electron discharge tubes possessing a high enough factor of 10 amplification, together with imperfect design in power units, this type of amplification has been commercially less acceptable than the more common transformer-coupled audio type of amplification. Of late, however, 15 a new type of resistance coupling has made its appearance which differs from the accepted type of resistance coupling, wherein the usual anode and control electrode resistors are coupled together by means of a coupling capacity.

As far as the prior art is concerned, this system of direct coupling, or resistance amplification, is well known. However, the introduction of tubes possessing a high factor 25 of amplification, together with devices for procuring very high voltages from a power source have served to facilitate the design of a direct coupled system of amplification wherein the anode of a preceding tube is directly coupled to the grid of a succeeding tube with no transformer or condenser between, thus producing a system capable of both amplification and detection-amplification. This improved type of direct coupled 30 audio amplification is capable of varied usage, particularly where amplification with a minimum level of distortion is desired.

Now, I have discovered a method of, and devised means for, applying the principles 40 of the direct coupled audio amplifier to produce a fairly sensitive receiving circuit of compact and simple construction, the arrangement employed consisting in feeding back energy from the output circuit of the 45 first stage of the direct coupled amplifier to the input circuit of the first stage, and in like phase with the energy in the said input circuit.

Accordingly, it is one of the main objects 50 of the present invention to provide a method

of, and means for, receiving modulated radio frequency signals which consists in collecting the signal energy at a desired frequency, detecting the energy, impressing the detected energy upon the input circuit of an electron 55 discharge tube directly coupled to the output circuit of the detecting tube, and simultaneously feeding back energy from the detector output circuit to the detector input circuit in regenerative phase with the input 60 energy.

Another important object of the present invention is to provide in a radio receiving circuit a direct coupled amplifier consisting of at least two electron discharge tubes, the 65 anode of one tube being directly connected to the control electrode of the succeeding tube, with no transformer or condenser between them, the first tube having associated therewith a path for feeding back energy 70 from the output thereof to its input circuit in regenerative phase with the energy in the input circuit.

Another object of the invention is to provide an audio amplification system which 75 comprises at least two electron discharge tubes, one of said tubes being a screen grid tube, and the other tube being a pentode tube, the anode of the screen grid tube being directly connected to the control electrode of 80 the pentode tube, the electrodes of both tubes having potential supplied thereto from a common potentiometer connected across the power source, the screen element circuit of the first tube being utilized to regenerate the 85 input circuit of the tube, where the anode circuit of the latter has so high a resistance in it that there is not enough anode current to produce regeneration satisfactorily.

Still another important object of the invention is to provide a radio receiving circuit consisting of a stage of tuned radio frequency amplification, a tetrode having a tuned input circuit coupled to the first stage, and a pentode directly coupled to the output 95 circuit of the tetrode, and means in series in the screen element circuit of the tetrode for feeding back energy from the output circuit of the tetrode to its input circuit, the electrodes of the tetrode and pentode having 100

potential supplied thereto from a common potentiometer connected across a power source.

Still other objects of the invention are to 5 improve generally the efficiency, simplicity and compactness of radio receivers, and to provide a receiving circuit which is not only satisfactory for use where high quality reproduction is desired, but is reliable in operation, and economically assembled and manufactured.

The novel features which I believe to be characteristic of my invention are set forth in particularity in the appended claims, the 15 invention itself, however, as to both its organization and method of operation will best be understood by reference to the following description taken in connection with the drawing in which I have indicated diagrammatically one circuit organization whereby my invention may be carried into effect.

Referring to the accompanying drawing there is shown a grounded antenna circuit A, G, coupled, as at M, to the input circuit 25 of an electron discharge tube 1, preferably a tetrode of the screen grid type, the inductance coil 2 in the input circuit being tuned by a variable condenser 3. The cathode of the tube 1 is preferably heated from a 30 source of alternating current (not shown), the screen element and anode of the tube 1 receiving potential from sources of positive potential (not shown).

The anode potential is applied to the anode of tube 1 through a primary coil 4, the latter being coupled with the secondary coil 5 of a radio transformer T. The coil 5 is connected in the input circuit of a second 40 tetrode 6, also of the screen grid type, by utilizing an indirectly heated cathode 7. The coil 5 is tuned by a variable condenser 8, the rotors of the condensers 3 and 8 being operated by a common uni-control mechanism 9, shown in dotted lines.

45 The heater filament 10 of the tube 6 receives power from a source of alternating current energy (not shown), it being noted that this source can be the same source which supplies power to the cathode of tube 1. The 50 screen element 11 of tube 6 has connected in series therewith a tickler inductance coil 12, inductively coupled with the coil 5, one terminal of the coil 12 being adjustably connected by a lead 13 to a resistor R₁, the latter 55 being preferably part of a potentiometer mechanism generally denoted by the letter P, the latter being preferably connected across the terminals of any well known type of power filter (not shown). The tickler coil 60 12 is preferably made adjustable so as to vary the degree of regeneration employed.

The anode 14 of the tube 6 is directly connected by a lead 15 to the control electrode 16 of a pentode tube 17. The pentode tube 17 65 also includes a cathode 18 heated from a

source of alternating current (not shown). This source is preferably the same source which heats the filaments of tubes 1 and 6, the cathode 18 receiving potential from the potentiometer P, by means of a lead 19 adjustably connected at one terminal to a resistor portion R₄, and its other terminal connected to the electrical mid-point of an inductance coil 20 connected across the terminals of cathode 18.

70 The screen element 21 of the pentode 17 is adjustably connected by a lead 22 to a resistor portion R₅ included in the potentiometer P. A space charge electrode 23 is disposed between the screen element 21 and the anode in a manner well known to those skilled in the art, and is connected to the cathode 18. The output circuit of the pentode 17 is adapted for connection to any well known type of utilization means such as a loud speaker, head phones and the like.

75 The lead 15 is tapped by a lead 24, and adjustably connected to the resistor R₄, the lead 24 including a high resistance R₆, the adjustable contact of the lead 24 being connected to a point, on the resistor R₄, of more positive potential than the adjustable contact point of the lead 19. The potentiometer P further includes a resistor R₂ and a resistor R₃, both connected in series with each other, and in series with the resistors R₁, R₄, and R₅, the latter three resistors also being connected in series. The cathode 7 of tetrode 6 is connected, by means of a lead 24, to one terminal of the resistor R₁, the lead 24 including in series with the cathode, a resistor R₇.

80 The cathode 7 is also connected to an adjustable contact arm 25, by means of a lead 26, the latter including a capacity C in series between the cathode and contact arm 25. It will be noted that the control electrode of tetrode 6 is negatively biased by adjustably connecting it to resistor R₁ by means of a lead 27, the lead including the inductance coil 5 in series with the control electrode. As stated heretofore, the screen element 11 of the tetrode 6 is adjustably connected to the resistor R₁, by means of a lead 13.

85 As an explanation of how the direct coupled amplifier operates, reference will now be made to the elements specifically shown in the drawing. The resistor R₇ cooperates with the resistor R₁ to develop initial grid bias for the tetrode 6, and to automatically vary the bias for what may be termed "drift correction" or stabilization. It is, also, to be noted that the lead 27 is adjustably connected to the resistor R₁, in order to insure a proper initial negative bias on the control electrode.

90 For example if the resistor R₇ develops a negative potential of about 16 volts with respect to the control electrode of the tetrode 6, this will be opposed by a positive potential

of about 14 volts in resistor R_1 , thereby providing an initial negative bias of about two volts for the control electrode of the tetrode 6. It is, of course, obvious that means is thus provided for maintaining the bias on the said control electrode by adjusting the lead 27 along the resistor R_1 . The resistors R_4 and R_5 divide the anode voltage of pentode tube 17 into two portions, with the junction 10 at the point 30 where the lead 24, which contains the high resistance R_6 , is connected on the resistance R_4 , thus giving a sufficient voltage drop between point 30 and point 31.

The latter point 31 is the point on the resistance R_4 to which the lead 19 is connected from the cathode connection on the electrical mid-point of inductance 20. This insures a drop of about 50 volts, while increasing the current drain on the power filter by a negligible amount. The leads 24 and 19 are 20 adjustably connected to the resistor R_4 , in order to insure securing proper negative bias on the control electrode 16 of the pentode 17.

The high resistance R_6 between the output 25 circuit of tetrode 6 and the input circuit of the pentode 17 results in a very high amplification gain, and it is because this resistance is so high that it is necessary to connect the lead 24 to a point 30 on the resistor R_4 , which 30 is a point of more positive potential than the point 31 to which the cathode is connected. The resistor R_3 is employed to aid in securing a proper voltage difference between the cathode 7 of the tetrode 6 and the cathode 18 35 of the pentode 17.

Hum in the amplifier, this hum arising most readily in the tetrode 6 which acts as a detector as well as an amplifier, is minimized by means of the series connection consisting 40 of the capacity C and the adjustable resistance 25, R_2 , the contact arm 25 being adjusted to the critical point which will result in a point of minimum hum. It will be obvious that the resistor R_2 will take care of a 45 great deal of the hum apparent in the detector output of even a poorly filtered receiver.

To illustrate the values of the resistors employed, it is noted herein that the resistor R_7 50 may have a value of 50,000 ohms; the resistor R_1 a value of 425 ohms; the resistor R_2 a value of 200 ohms; the resistor R_3 a value of 775 ohms; the resistor R_4 a value of 29,700 ohms; the resistor R_5 a value of 55 100,000 ohms; and the resistor R_6 a value of 500,000 ohms. It is to be clearly understood 60 that these values are given merely for the purpose of illustration, and can be varied in any desirable manner to secure high gain without distortion.

The use of the pentode tube 17 results in a very great increase in the amplification, and is about equal to adding another stage of audio amplification. The operation of the 65 receiver is greatly improved by the utiliza-

tion of the tickler coil 12 in series with the screen 11 of the tube 6. This connection still further increases the sensitivity of the receiver, thus permitting the use of only two tubes, one a tetrode, and the other a pentode, 70 it being readily apparent that since the tetrode 6 also operates as a detector stage, the antenna circuit could be coupled directly to the tuned input circuit of the tetrode 6 and a fairly sensitive receiver still had. 75

However, with the addition of a stage of tuned radio frequency amplification employing a screen grid tube ahead of the tetrode 6, an excellent, and yet inexpensive, receiving circuit is produced. This circuit, it will be 80 further observed, lends itself readily to regeneration connection in the detector-amplifier stage employing the tetrode 6, where the anode circuit includes a resistance which is so high that there is not enough anode current to automatically produce regeneration satisfactorily; the utilization of a tetrode of the screen grid type, it being readily apparent, successfully maintaining feed-back 85 through the inter-electrode capacities of the 90 tube at a safe minimum value.

While I have indicated and described one arrangement for carrying my invention into effect, it will be apparent to one skilled in the art that my invention is by no means 95 limited to the particular organization shown and described, but that many modifications may be made without departing from the scope of my invention as set forth in the 100 appended claims.

What I claim is:

1. A radio receiving circuit comprising means for collecting signal energy, means for detecting the collected signals including an electron discharge tube provided with a screen 105 electrode and having a tuned input circuit, a pentode tube having its control electrode directly connected to the anode of the detecting tube, and means for feeding back energy from the screen circuit of the detaching tube 110 to its tuned input circuit.

2. In combination, in a receiving circuit a combined detector and amplifier consisting of a tetrode having a screen electrode and a 115 tuned input circuit, a pentode output tube having its control electrode directly connected to the anode of the tetrode, and means for feeding back energy from the screen circuit of the tetrode to its tuned input circuit.

3. In combination, an antenna circuit, a stage of tuned radio frequency amplification including an electron discharge tube coupled thereto, an electron discharge tube provided with a tuned input circuit coupled to the 125 first stage, the second tube including a screen element, a third electron discharge tube having its control electrode directly connected to the anode of the second tube, means for regeneratively connecting the screen element of 130

the second tube to its tuned input circuit, a common source of potential for the second and third tubes, a common potentiometer connected across said source, the screen element of the second tube and the control electrode of the third tube both deriving potential from said common potentiometer.

4. In combination, in a receiving circuit, a regenerative screen grid detector, and a pentode output tube having its control electrode directly connected to the anode of the detector, a potential supply potentiometer, all the circuits of said detector and output tube being connected to the potentiometer, and means adjustably connecting the detector screen grid to the potentiometer.

5. A radio receiving circuit comprising a screen grid tube having a tuned input circuit, an audio frequency amplifier connected in the anode circuit of said tube, and an inductive reactance in the screen element circuit of said tube coupled in regenerative phase to said input circuit.

6. A radio receiving circuit comprising a screen grid tube having a tuned input circuit, an audio frequency amplifier connected in the anode circuit of said tube, and mutual impedance between the screen element circuit and the tuned input circuit of said tube, a potential supply potentiometer, the electrodes of said tube and amplifier being connected to the potentiometer, and means for adjustably connecting the screen element to the latter.

35 7. In combination, a source of radio frequency energy, a screen grid tube provided with a tunable input circuit coupled to said source, a power amplifier tube including a screen grid disposed between the cathode and anode thereof and a shield electrode, at cathode potential, between the screen and anode, a source of energizing current common to the circuits of said tubes, means for directly connecting the anode of said first tube to the control electrode of the amplifier tube, and means including a high resistance, connecting said anode and control electrode to said energizing current source.

8. In a radio receiver, a detector stage including a screen grid tube provided with a tunable input circuit, an amplifier tube, a source of energizing current for the circuits of said tubes, means conductively coupling the anode of said detector tube and the control grid of the amplifier tube, additional means, including a high impedance, connecting said conductive coupling to said source, and means in the screen circuit of said detector tube to secure regeneration.

60 9. In a radio receiver, a detector stage including a screen grid tube provided with a tunable input circuit, a power pentode amplifier tube, a source of energizing current for the circuits of said tubes, means conductively coupling the anode of said detector tube and

the control grid of the amplifier tube, additional means, including a high impedance, connecting said conductive coupling to said source, and means in the screen circuit of said detector tube to secure regeneration.

10. In a radio receiver, a detector stage including a screen grid tube provided with a tunable input circuit, an amplifier tube, a source of energizing current for the circuits of said tubes, means conductively coupling the anode of said detector tube and the control grid of the amplifier tube, additional means including an impedance, so high that there is insufficient anode current in the detector stage to produce regeneration satisfactorily, connecting said conductive coupling to said source, and means in the screen circuit of said detector tube to secure regeneration.

11. In a radio receiver, a detector stage including a screen grid tube provided with a tunable input circuit, an amplifier tube, a source of energizing current for the circuits of said tubes, means conductively coupling the anode of said detector tube and the control grid of the amplifier tube, additional means, including a high impedance, connecting said conductive coupling to said source, and means in the screen circuit of said detector tube to secure regeneration and a stage of tuned radio frequency amplification including a screen grid tube coupled to said detector input circuit.

12. An electric circuit comprising an electron discharge tube having an emission cathode, an anode, a control grid, and a screen grid, a tunable input circuit connected between said cathode and said control grid, an output circuit connected between said cathode and said anode, a source of energizing current for the anode, control grid and screen grid circuits of said tube, said output circuit having an impedance so high that there is not enough anode current to produce regeneration satisfactorily, and means associated with said screen grid circuit for feeding energy to said input circuit in regenerative phase with the energy transmitted from said input circuit to said output circuit.

13. In combination with a potential supply potentiometer, a screen grid tube having a tunable input circuit, connections between the electrodes of the tube and the potentiometer to establish said electrodes at desired potentials, a source of signal energy coupled to the said input circuit, a pentode amplifier tube, means for directly connecting the control grid of the pentode tube to the anode of the screen grid tube, connections between the electrodes of the pentode tube and the potentiometer to fix the pentode electrodes at desired potentials, the connection between the potentiometer and said anode and control grid including a high impedance, and the connection between the screen grid of said

- first tube and said potentiometer being adjustable.
14. In combination with a potential supply potentiometer, a screen grid tube having a tunable input circuit, connections between the electrodes of the tube and the potentiometer to establish said electrodes at desired potentials, a source of signal energy coupled to the said input circuit, a pentode amplifier tube, means for directly connecting the control grid of the pentode tube to the anode of the screen grid tube, connections between the electrodes of the pentode tube and the potentiometer to fix the pentode electrodes at desired potentials, the connection between the potentiometer and said anode and control grid including a high impedance, means for regeneratively coupling the screen grid and input circuits of said first tube, and the connection between the screen grid of said first tube and said potentiometer being adjustable.
15. In combination, a source of radio frequency energy, a screen grid detector tube provided with a tunable input circuit coupled to said source, a power amplifier tube including a screen grid disposed between the cathode and anode thereof and a shield electrode, at cathode potential, between the screen and anode, a source of energizing current common to the circuits of said tubes, means for directly connecting the anode of said first tube to the control electrode of the amplifier tube, and means including a high resistance, connecting said anode and control electrode to said energizing current source.
16. In combination, a source of radio frequency energy, a screen grid tube provided with a tunable input circuit coupled to said source, a power amplifier tube including a screen grid disposed between the cathode and anode thereof and a shield electrode, at cathode potential, between the screen and anode, a source of energizing current including a potentiometer common to the circuits of said tubes, means for directly connecting the anode of said first tube to the control electrode of the amplifier tube, and means including a high resistance, connecting said anode and control electrode to said energizing current source.
17. In combination, a source of radio frequency energy, a screen grid tube provided with a tunable input circuit coupled to said source, a power amplifier tube including a screen grid disposed between the cathode and anode thereof and a shield electrode, at cathode potential, between the screen and anode, a source of energizing current common to the circuits of said tubes, means for directly connecting the anode of said first tube to the control electrode of the amplifier tube, and means including a high resistance, connecting said anode and control electrode to said energizing current source, said source including a potentiometer, the cathode of the said power tube

being connected to said potentiometer, the screen grid of the first tube being connected to a point on said potentiometer which is negative with respect to the point on the potentiometer to which said power tube cathode is connected.

18. In combination, a source of radio frequency energy, a screen grid detector tube provided with a tunable input circuit coupled to said source, a power amplifier tube including a screen grid disposed between the cathode and anode thereof and a shield electrode, at cathode potential, between the screen and anode, a source of energizing current common to the circuits of said tubes, means for directly connecting the anode of said first tube to the control electrode of the amplifier tube, and means including a high resistance connecting said anode and control electrode to said energizing current source; and a screen grid radio frequency amplifier provided with a tunable input circuit disposed between said source and detector input circuit.

DISCLAIMER

1,910,500.—*Walter Van B. Roberts, Princeton, N. J.* RADIO RECEIVING CIRCUIT.
Patent dated May 23, 1933. Disclaimer filed November 14, 1935, by
the assignee, *Radio Corporation of America*.

The disclaimer filed on September 25, 1935, was in error in that the language of said claims was not correctly recited;

That it was the intention of the undersigned assignee to disclaim the subject matter of claims 6, 8, 10, and 12 of said Letters Patent and not the language of the claims recited in the disclaimer filed September 25, 1935;

That said error arose through inadvertence, accident, or mistake and without any fraudulent or deceptive intention.

Your Petitioner, therefore, hereby retracts that portion of the disclaimer filed September 25, 1935, which purported to recite the language of claims 6, 8, 10, and 12 and hereby enters this disclaimer to that part of the claims in the specification of said Letters Patent which is in the following words, to wit:

"6. A radio receiving circuit comprising a screen grid tube having a tuned input circuit, an audio frequency amplifier connected in the anode circuit of said tube, and mutual impedance between the screen element circuit and the tuned input circuit of said tube, a potential supply potentiometer, the electrodes of said tube and amplifier being connected to the potentiometer, and means for adjustably connecting the screen element to the latter."

"8. In a radio receiver, a detector stage including a screen grid tube provided with a tunable input circuit, an amplifier tube, a source of energizing current for the circuits of said tubes, means conductively coupling the anode of said detector tube and the control grid of the amplifier tube, additional means, including a high impedance connecting said conductive coupling to said source, and means in the screen circuit of said detector tube to secure regeneration."

"10. In a radio receiver, a detector stage including a screen grid tube provided with a tunable input circuit, an amplifier tube, a source of energizing current for the circuits of said tubes, means conductively coupling the anode of said detector tube and the control grid of the amplifier tube, additional means including an impedance, so high that there is insufficient anode current in the detector stage to produce regeneration satisfactorily, connecting said conductive coupling to said source, and means in the screen circuit of said detector tube to secure regeneration."

"12. An electric circuit comprising an electron discharge tube having an emission cathode, an anode, a control grid, and a screen grid, a tunable input circuit connected between said cathode and said control grid, an output circuit connected between said cathode and said anode, a source of energizing current for the anode, control grid and screen grid circuits of said tube, said output circuit having an impedance so high that there is not enough anode current to produce regeneration satisfactorily, and means associated with said screen grid circuit for feeding energy to said input circuit in regenerative phase with the energy transmitted from said input circuit to said output circuit."
